UNITED STATES PATENT OFFICE

CHARLES L. KRISTOFFERSON, OF INDIANAPOLIS, INDIANA.

RAIL-JOINT.

1,124,919.

Specification of Letters Patent.

Patented Jan. 12, 1915.

Application filed August 24, 1912, Serial No. 716,820. Renewed June 11, 1914. Serial No. 844,582.

To all whom it may concern:

Be it known that I, CHARLES L. KRISTOFFERSON, citizen of the United States, residing at Indianapolis, in the county of Marion and State of Indiana, have invented certain new and useful Improvements in Rail-Joints, of which the following is a specification.

My invention relates to new and useful improvements in rail joints and more particularly to rail joints of the chair type; and the object of my invention is to provide a rail joint having a base plate and an integrally formed splice bar bearing against one side of the rail ends, a second splice bar adapted to be secured against the other side of the rail ends, and a key plate for locking the second splice bar in position, thereby securing the rail ends against both vertical and transverse movement.

A further object of my invention is to so construct the separable splice bar as to provide a head which will bear beneath and against the outer face of the heads of the rail ends to additionally brace the same.

With these and other objects in view, my invention will be more fully described, illustrated in the accompanying drawings and then specifically pointed out in the claims which are attached to and form a part of this application.

In the drawings:

Figure 1 is a perspective view of my improved rail joint in use; Fig. 2 is a vertical transverse section taken through the rail joint; Fig. 3 is a detail perspective of the parts making up the joint.

For the sake of clearness I have illustrated the rail joint in use, the ties being shown at 10 and the abutting rail ends at 11. The joint proper consists primarily of a base plate 12 having an integrally formed splice bar 13, a second splice bar 14, and a key plate 15.

The base plate 12 is so proportioned as to form a seat for the base of the rail ends and to extend at its free edge considerably beyond the outer rail flange, the length of the base plate being such as to seat upon two or more ties. This base plate 12 is provided at its inner edge with the integrally formed splice bar 13 which is shaped to conform with the inner face of the rail ends having an inwardly directed portion which engages over the inner flange of the rail and which terminates in an upwardly directed portion

which bears at its upper and lower edges against the web of the rail and the free edge of which bears beneath the inner portion of the head of the rail as shown at 16. This splice bar is provided with a plurality of spaced bolt receiving bores 17, and the rail ends are provided with similarly positioned bores 18.

The separable splice bar 14 is identical in construction with the splice bar 13 with the exception that it is not attached to the base plate 12 and with the further exception that its upper end is extended outwardly and upwardly to form a grooved head 19 which bears beneath and against the outer face of the heads of the rail ends, as best shown in Fig. 2. This splice bar 14 is provided with bores 20 which, when the splice bar is in position, are in alinement with the bores 18 of the rail and the bores 17 of the splice bar 13.

The base plate 12 is provided immediately adjacent the lower end of the lower edge of the splice bar 14 with a plurality of longitudinally spaced apart slots 21, and the key plate, previously designated by the numeral 15, is provided at its lower edge with similar spaced apart, downwardly and outwardly directed toes 22 adapted to be inserted through the slots 21 and to engage against the portions of the base plate lying between said slots and the free edge of the plate, as best shown in Fig. 2 of the drawings. This key plate is shaped to conform with the outer face of the splice bar 14 and has its upper end grooved, as at 23, to bear beneath the head 19 of the said splice bar. The key plate is also provided with bores 24 in alinement with the bores of the splice bars and rail ends, and when swung to active position the splice bars, key plate, and rail ends are all secured against independent movement by bolts 25 passing through the alined bores of said members and provided with clamping nuts 26.

The rail joint is preferably secured in place upon the ties by means of the customary spikes 27, and the free edge of the base plate 12 may be provided with spaced recesses 28 for the reception of these spikes, the engagement of the spikes against the sides of the recesses preventing all longitudinal creeping of the rail joints.

As will be readily seen, the splice bars being stiffened by the base plate and key plate absolutely prevent all transverse movement

of the rail ends, while the base plate being stiffened by the other members of the joint prevents all other movement, any downward movement of the rail ends being prevented by the seating of the heads of the rail ends upon the upper edge of the splice bar 13 and in the head 19 of the splice bar 14.

The engagement of the toes 22 of the key plate with the base plate 12 braces the rail ends against turning and thereby relieves the strain from the juncture of the base plate and splice bar 13.

It will of course be understood that as many toes may be provided upon the key plate as are desired, but it is preferable to so arrange these toes that they will lie between the ties, as shown in Fig. 1, thus doing away with the necessity of shaping the ties to provide seats for the toes.

Having described my invention, what is claimed is:

1. In a rail joint, the combination with abutting rail ends, of a base plate having longitudinally spaced slots formed adjacent one edge, a splice bar formed integrally with one edge of the base plate and bearing against one side of the rail ends and beneath the heads of the rails, a detachable splice bar bearing against the opposite side of the rail ends and provided with an outwardly and upwardly directed, longitudinally grooved head in which and against which the adjacent sides of the heads of the

rail seat, a key plate with toes formed thereon for engagement with said slots, said key plate bearing against the outer face of the second-named splice bar, and bolts passed through the key plate, splice bars and rail webs to secure the parts together. 35

2. A rail joint including a base plate having longitudinally spaced slots formed adjacent one edge, splice bars, a key plate bearing against the adjacent splice bars throughout the length thereof, and toes formed on said key plate for detachably holding the said base plate and splice bars in assembled relation by engagement through the slots in said base plate. 40

3. A rail joint including a base plate having longitudinally spaced slots formed adjacent one edge, splice bars, a single key plate for holding the splice bars in clamping engagement with the rails, said key plate bearing against the adjacent splice bar throughout the length thereof, and toes 50 formed on said key plate for detachably holding the splice bars and base plate in assembled relation, said toes being engageable with the base plate by insertion through the slots therein. 60

In testimony whereof I affix my signature in presence of two witnesses.

CHARLES L. KRISTOFFERSON. [L. S.]
